MAGNET KNITTING MILLS, OF CLINTON, TENNESSEE, A CORPORATION OF TEN-
NESSEE.

BACKWINDING MACHINE.

Application filed March 22, 1926. Serial No. 96,591.

This invention relates to backwinding machines and more particularly to a machine for backwinding the threads of a knit fabric or the like.

It has heretofore been proposed to provide a machine for backwinding the yarn of a flat knit fabric, but machines of this type are generally not adapted for backwinding threads of the finer grades of fabric or for 10 backwinding the threads of a tubular fabric. It has further been proposed to backwind the threads or yarns of a tubular knit fabric, but the machines for this purpose with which we are acquainted backwind the 15 threads on spools or tubes so that in order to obtain the recognized advantages of knitting from cones, the threads on the tubes or spools must be rewound on cones, which necessitates the use of additional equipment 20 and increases the cost of the reclaiming process. It has further been proposed to backwind a single thread of a tubular fabric on a cone, but machines of this type are not adapted for backwinding and recovering 25 separately a plurality of threads of a knit fabric composed, for example, of silk and cotton, or silk and rayon, or various combinations of threads or yarns of different materials.

The principal objects of this invention are to provide a machine which enables separate threads or yarns of a knit tubular fabric to be backwound directly on cones; which affords means for backwinding directly on 35 cones not only separate threads or yarns of the usual tubular knit fabric, but also the separate threads or yarns of what is known as a plated fabric; which insures that the several threads will be led in different direc- 40 tions from spaced points on the unravelling edge of the fabric and at the same time always be supported and guided in the plane of said unravelling edge of the fabric; which exerts a positive braking action on 45 the fabric support and regulates the tension of the unravelling thread; and which is simple in construction, highly efficient in operation and inexpensive to install and maintain.

In order to more clearly understand this 50 invention, reference may be had to the accompanying drawings which illustrate a

backwinding machine embodying the inventive idea and wherein

Fig. 1 is a detailed perspective view of the machine;

55

Fig. 2 is an enlarged horizontal sectional view on the line 2—2 of Fig. 4;

Fig. 3 is a horizontal sectional view on the line 3—3 of Fig. 4; and

Fig. 4 is a vertical sectional view on the 60 axis of the fabric support or drum shown in Fig. 1.

Referring to the drawings, wherein like reference characters designate like parts throughout the several views, the mechanism 65 of the present invention is preferably mounted on a table 5, the legs 6, 6 of which are connected by cross pieces 7, 7 and braced through the medium of tie members 8, 8 secured in any suitable manner to the legs 6, 6, 70 cross pieces 7, 7, and the upper part of said table.

The source of power for driving the various instrumentalities mounted on the table 5 preferably comprises a power transmitter 9 75 of any well known construction which may be driven from an electric or other suitable motor (not shown) and controlled through the medium of a lever 10 rigidly secured on a shaft 11 connected with the clutch of the power transmitter and journaled in suitable

bearings in a bracket 12 bolted or otherwise suitably secured on one end of the table 5.

The power transmitter 9 includes the usual change speed pulleys 13, 13 over one of

which passes a belt 14, said belt also passing over a grooved pulley (not shown) fixed on a shaft 15, journaled in bearings 16, 16 carried by the cross pieces 7, 7. The shaft

15 also has fixed thereon a pair of grooved pulleys which preferably differ in size with

respect to each other and one of which is indicated at 17. Passing around these pulleys are belts 18, 18 which run through suitable openings in the top of the table 5 and

pass around pulleys 19, 19 fixed on shafts

20, 20 which are spaced in substantially parallel relation and journaled in brackets 21, 21 bolted or otherwise suitably secured on

the table 5.

95

The shafts 20, 20 have fixed thereon cone shaped friction members 22, 22 for driving

100

thread or yarn holders 23, 23 which, in accordance with the present invention, are also cone shaped and mounted on cone shaped spindles 24, 24 journaled in suitable bearings in arms 25, 25. The arms 25, 25 are pivotally mounted at 26, 26 on brackets 27, 27 bolted or otherwise suitably secured to the table 5, and said arms are preferably provided with weights 28, 28 by means of which frictional engagement of the cones 29, 29 of thread or yarn with the cones 22, 22 may be regulated as desired. During pivotal movement of the arms 25, 25 caused by gradual increase of the size of the cones 29, 29 the free 10 ends of said arms are guided in slots 30, 30 formed in the outer bent extremities 31, 31 of brackets 32, 32 bolted or otherwise suitably fastened to the table 5. As a further means of guiding the arms 25, 25, the brackets 32, 32 are preferably provided with upwardly bent inner extremities 33, 33, having reduced portions 34, 34 which slidably engage the arms 25, 25.

One extremity of the shaft 15 projects 25 through the adjacent bearing 16 and has fixed thereon a spur gear 35, which meshes with a larger spur gear 36 fixed on a shaft 37 journaled in a bearing 38 carried on the adjacent cross piece 7. The gears 35, 36, together with gears 39 and 40, form part of a speed reduction mechanism, the operation and construction of which is well known and understood in the art and needs no detailed explanation in so far as the present 35 invention is concerned. The gear 36, however, has rigidly secured on the outer face thereof, as by set screws 41, 41, an arm 42, the slotted outer end of which is pivotally connected at 43 with the lower end of a link 44. The upper end of the link 44 is pivotally connected at 45 with the free end of a lever 46 fixed on a rock shaft 47. The rock shaft 47 is journaled in suitable bearings in a pair of brackets, one of which is indicated 45 at 48, said brackets being bolted or fastened in any other desired manner on the table 5. The rock shaft 47 has fixed thereon a lever 49 the free end of which is pivotally connected at 50 with one end of a link 51 (Fig. 2). 50 The opposite end of the link 51 is pivotally connected at 52 with one end of a pawl carrying lever 53 loosely mounted on the lower unthreaded portion of a screw shaft 54.

The opposite end of the lever 53 carries a 55 spring pressed pawl 55 arranged to engage the teeth 56 of a ratchet 57 fixed on the screw shaft 54 between the lever 53 and a base plate 58 through which the lower end of said screw shaft projects (Fig. 4). The base plate 58 is preferably provided with circular pads 59 and 60 which engage the table 5 and together with base plate 58 serve to support various devices carried by the latter above the table 5. The pad 60 further serves as a 60 bearing for the screw shaft 54, and for this

purpose is recessed at 61 to receive the reduced lower end 62 of said shaft. A collar 63 fixed on the shaft 54 between the base plate 58 and the pad 60 serves to prevent displacement of the shaft 54 with respect to the base plate 58.

In accordance with the present invention, movable means are provided for supporting and guiding the separate unravelled threads or yarns in the plane of the unravelling edge 75 of the fabric so that as said threads or yarns are being unravelled they will follow the movement of the unravelling edge of the fabric and at the same time be led in different directions away from spaced points on 80 said unravelling edge in order to avoid interference between the threads or yarns during unravelling and winding of the same on their respective conical holders 23, 23. The means last referred to preferably consists, in addition to the screw shaft 54 and the pawl and ratchet mechanism for rotating the same, of a carriage 64 provided with an opening 65 of greater diameter than that of the screw shaft 54 and through which the latter projects. The carriage 64 has pivotally mounted thereon at 66 a lever 67 provided with a substantially semi-circular off-set thread engaging portion 68 which when engaged with the threads of the shaft 54, as by turning the 95 lever 67 in one direction about the pivot 66, serves to operatively connect the carriage 64 with said shaft causing the carriage to move downwardly as the shaft is rotated in the direction of the arrow (Fig. 2). The off-set portion 68 of the lever 67 is preferably retained in engagement with the threaded portion of screw shaft 54 by a latch 68' pivotally mounted at 68'' on the carriage 64. In order to prevent the carriage 64 from tilting with 100 respect to the screw shaft 54, said carriage is provided with an apertured boss 69 which is slidably engaged with a guide 70, the lower threaded end of which passes through a suitable opening in the base plate 58 and is threaded in a socket 71 secured in any suitable manner to the table 5. The upper end of the guide 70 has fixed thereon a bearing plate 72 in which the upper end of the screw shaft 54 is journaled. The carriage 64 is 110 provided with a yoke 73, the arms 74, 74 of which embrace a fabric support or drum 75 disposed vertically between the two sets of conical driving and driven elements 22, 23, 22, 23 and substantially equi-distant from 120 each set of the latter. The ends of the yoke arms 74, 74 are provided with thread supports and guides 76, 76 which, as the carriage 64 moves downwardly, are always disposed in the plane of the unravelling edge 77 of a 125 hose clipping or other tubular knitted fabric 78 placed on the drum 75, and lead the threads or yarns 79, 79 of said fabric in different directions from spaced points 80, 80 on the unravelling edge 77 as said threads 130

or yarns are being unravelled and backwound on the cones 23, 23.

In accordance with the present invention, the drum 75 is rotated by the unravelling and backwinding of the threads or yarns 79, 79 on the cones 23, 23 and the spaced relation of the points 80, 80 on the unravelling edge 77 from which said threads or yarns are drawn, is always maintained substantially the same so that interference between or entanglement of the threads is thereby avoided. For this purpose, the drum is preferably supported for rotation on a plurality of anti-friction elements 81, 81 retained in the groove 82 of a raceway 83 by the weight of the drum and engaging the under surface of the closed lower end 84 thereof. The raceway 83 is fixed on a collar 85, a reduced threaded extension 86 of which passes through a suitable opening in the base plate 58 and has threaded thereon a nut 87 by means of which the collar 85 is securely clamped to said base plate. The collar 85 has fixed therein a stationary rod 88 which extends loosely through an opening 89 formed in the closed lower end 84 of the drum and located on the longitudinal axis thereof. In order to prevent accidental displacement of the drum 75 from its anti-friction support, the rod 88 is preferably extended upwardly within the drum and provided with a spider 91, the hub 90 of which is fixed on the upper end of the rod 88. The diameter of the rim 91' of the spider is slightly less than that of the drum 75, as clearly shown in Fig. 4, so that friction between the spider and drum during rotation of the latter is avoided.

In addition to the means above described for supporting and guiding the threads or yarns, means are also provided adjacent the winders 22, 22 for guiding said threads or yarns back and forth while being wound into cones on the conical holders 23, 23. The guiding means last referred to preferably comprises a pair of spaced levers 92, 92 fixed on the rock shaft 47 and having their free ends pivotally connected at 93, 93 with the adjacent extremities of links 94, 94. The opposite extremities of the links 94, 94 are pivotally connected at 95, 95 with thread guides 96, 96 provided therein with eyes 97, 97 through which the threads or yarns 79, 79 pass as they are being wound on the conical holders 23, 23. The thread guides 96, 96 are slidably mounted on tracks 98, 98 which are supported over the table 5 by brackets 99, 99 bolted or otherwise suitably secured to said table. It will thus appear that motion of the links 94, 94 received from the levers 92, 92 and rock shaft 47, is transmitted to the thread guides 96, 96 causing them to reciprocate along the tracks 98, 98 as the threads 79, 79 passing through the eyes 97, 97 of said guides are being wound on the conical holders 23, 23.

In accordance with the present invention, means are provided for exerting a positive braking action on the rotatable fabric support, in order to automatically regulate the tension of unravelling threads or yarns 79 and prevent the rotatable fabric support from overrunning the winding devices. For this purpose a spring or weight controlled brake of any suitable construction may be provided for engaging the drum, and as herein shown, said brake preferably comprises a lever 100 pivotally mounted at 101 on a bracket 102 secured in any suitable manner to the base plate 58 (Figs. 1 and 2). The lever 100 is provided at one end with a brake pad 103 which engages the lower closed end of the drum 75 and is automatically maintained in engagement therewith by an adjustable weight or spring (not shown).

In the operation of the machine, the shaft 47 is rocked by its connections with the gear 36 and this rocking movement of the shaft 47 is transmitted by the connections between the same and the pawl carrier 53 so as to impart a step by step rotation to the ratchet 57 and screw shaft 54. Rotation of the screw shaft 54 causes the carriage 64 to move downwardly on said shaft as the threads or yarns 79, 79 are being unravelled from the fabric 78 and backwound on the conical holders 23, 23. This movement of the carriage 64, screw shaft 54, and ratchet 57 is so timed with respect to the rotary movement of the cones 22, 22 that the carriage 64 and thread guides 76, 76 are always disposed substantially in the plane of the unravelling edge 77 of the fabric 78. If, in the operation of the machine above described the threads 79, 79 are of different materials such as silk and cotton, or silk and rayon, or various combinations of threads of different materials, it has been found, particularly with what is known as a plated fabric, that while the threads of different materials will unravel at a fixed ratio, they do not unravel at the same rate. In order to compensate for the difference in rate of unravelling of threads embodied in fabric such as last referred to, and at the same time maintain the proper ratio of movement between the carriage 64 and the cones 22, 22, the pulleys such as indicated at 17 for driving said cones, differ in size as respects each other so that the cones 22, 22 will be driven by the belts 18, 18 at speeds having a ratio therebetween corresponding with the difference in rate of unravelling of the separate threads of the knit or plated fabric.

While the mechanism herein disclosed is adapted for unravelling and backwinding two threads of a tubular knit or plated fabric, it will be readily appreciated that by the provision of additional thread guides and winding devices, a corresponding additional

number of threads of a tubular knit or plated fabric may be unravelled and backwound in an efficient manner. Moreover, it will appear that instead of unravelling and backwinding a plurality of threads, the mechanism may be employed to unravel and backwind a single thread of a tubular knit fabric. It is therefore to be expressly understood, that this invention is not limited to the particular mechanical embodiment set forth but that the inventive idea is susceptible of a variety of mechanical expressions within the limits of the appended claims.

What is claimed is:

15. 1. The combination with a plurality of spaced driven cone holders, of a rotatable drum mounted between said cone holders so that separate threads or yarns of a tubular fabric on said drum may be unravelled and backwound separately on cones carried by said folders.
20. 2. The combination with a plurality of spaced driving elements and a corresponding number of cone holders arranged to be driven thereby, of a drum rotatably mounted between the driving elements so that the threads or yarns of a tubular fabric on the drum may be unravelled and backwound separately on cones carried by said holders, and means for rotating said driving elements.
25. 3. In a machine of the character described, a winding device, a fabric holder arranged so that a thread or yarn of the fabric may be unravelled and backwound on said winding device, and movable means arranged adjacent the fabric holder and adapted to continuously guide the unravelling thread or yarn substantially in the plane of the unravelling edge of said fabric.
30. 4. In a machine of the character described, a winding device, a fabric holder arranged so that a thread or yarn of the fabric may be unravelled and backwound on said winding device, movable means adjacent the fabric holder for guiding the unravelling thread or yarn, and mechanism for moving the thread guiding means and adapted to continuously maintain the latter substantially in the plane of the unravelling edge of the fabric.
35. 5. In a machine of the character described, a rotatable drum adapted to support a tubular fabric, a device mounted for movement longitudinally of the drum and adapted to guide a thread or yarn as it is being unravelled from the tubular fabric on said drum, mechanism for moving the thread guiding device as the thread or yarn is being unravelled so as to continually maintain said device adjacent the plane of the unravelling edge of the fabric, and means for unravelling and backwinding said thread or yarn.
40. 6. In a machine of the character described,

a rotatable drum adapted to support a tubular fabric, a plurality of devices arranged for movement longitudinally of the drum and adapted to separately support and guide a plurality of threads or yarns being unravelled from tubular fabric on said drum, means for moving said devices to continuously maintain them adjacent the plane of the unravelling edge of the fabric, and a plurality of mechanisms for unravelling and separately backwinding said threads or

7. In a machine of the character described, a rotatable drum adapted to support a tubular fabric, a carriage mounted for movement longitudinally of said drum and provided with a pair of devices embracing the drum and adapted to guide a plurality of threads or yarns being unravelled from tubular fabric on the drum, means for moving said carriage and devices to continuously maintain the latter adjacent the plane of the unravelling edge of the fabric, and a plurality of mechanisms for unravelling and separately backwinding said threads or yarns.

8. In combination, a rotatable drum adapted to support a tubular fabric so that a thread or yarn thereof may be unravelled, a screw shaft rotatably supported adjacent said drum, and means mounted on said screw shaft and movable thereby so as to guide the thread or yarn substantially in the plane of the unravelling edge of the fabric.

9. In combination, a vertically disposed rotatable drum arranged to support a tubular fabric so that a thread or yarn thereof may be unravelled, movable means adjacent the drum for supporting and guiding the thread or yarn, and a pawl and ratchet mechanism adapted to move said means in accordance with the rate of unravelling of the thread or yarn.

10. In combination, a device arranged to support a fabric so that a thread or yarn thereof may be unravelled, movable means arranged to guide the thread or yarn being unravelled, and mechanism for moving said means adapted to maintain the same substantially in the plane of the unravelling edge of the fabric as the thread or yarn thereof is being unravelled.

11. In combination, a device arranged to support a fabric so that a plurality of threads or yarns thereof may be unravelled, a plurality of spaced movable devices arranged to support and guide the threads or yarns being unravelled, and mechanism for moving said devices adapted to maintain them substantially in the plane of the unravelling edge of the fabric as the threads or yarns are being unravelled.

12. In combination, a rotatable drum arranged to support a tubular fabric so that individual threads or yarns may be un-

- ravelled, a movably mounted yoke embracing said drum and provided on each arm thereof with means for guiding one of the threads or yarns, and operating mechanism for said yoke timed to move the same so as to maintain said means substantially in the plane of the unravelling edge of the fabric as the threads or yarns are being unravelled.
13. In combination, a fabric holder, means for guiding individual threads or yarns being unravelled from fabric on said holder, and mechanism for imparting step by step movement to said means so as to maintain the latter substantially in the plane of the unravelling edge of the fabric as the threads or yarns thereof are being unravelled.
14. In combination, a fabric holder, a carriage movably mounted adjacent the holder and provided with means for guiding a thread or yarn being unravelled from fabric on said holder, and mechanism for moving said carriage so as to maintain said guiding means substantially in the plane of the unravelling edge of the fabric as the thread or yarn is being unravelled, said mechanism including a screw shaft on which the carriage is mounted and a pawl and ratchet for turning said screw shaft.
15. In combination, a fabric holder, movable means for guiding a thread or yarn being unravelled from fabric on said holder, and devices for moving said means to maintain the same adjacent the plane of the unravelling edge of the fabric, said devices including a pawl and ratchet mechanism and a rock shaft for operating said pawl and ratchet mechanism.
16. In combination, a fabric holder, means for guiding a thread or yarn being unravelled from fabric on said holder, a screw shaft for moving said means relatively to the fabric-holder, a pawl and ratchet mechanism for turning said screw shaft, and a rock shaft for operating said pawl and ratchet mechanism.
17. In combination, a rotatable drum or the like for supporting a tubular fabric, a movable carriage having one or more thread guides thereon for guiding a thread or threads being unravelled from tubular fabric on said rotatable drum, a screw shaft for moving the carriage and said thread guides longitudinally of the drum, a pawl and ratchet mechanism for turning said screw shaft, a rock shaft for operating the pawl and ratchet mechanism, and means for rocking said last named shaft.
18. In combination, a fabric holder, a carriage having an opening therein, a screw shaft extending through said opening and adapted to be connected with the carriage to move it relatively to the fabric-holder, means for connecting the carriage with and for disconnecting the same from said screw shaft, and one or more devices on said carriage for guiding a thread or threads being unravelled from fabric on said holder.
19. In combination, a fabric holder, a guide arranged adjacent the fabric holder, a carriage slidably mounted on said guide and provided with one or more devices for guiding a thread or threads being unravelled from fabric on said holder, and means for moving the carriage so as to maintain the thread guiding device or devices substantially in the plane of the unravelling edge of the fabric as the thread or threads thereof are being unravelled.
20. In combination, a fabric holder, a guide arranged adjacent said holder, means slidably mounted on said guide for guiding a thread or threads being unravelled from fabric on said holder, and a screw shaft for moving said means so as to maintain the same substantially in the plane of the unravelling edge of the fabric as the thread or threads are being unravelled.
21. In combination, a fabric holder, a guide arranged adjacent said holder, means slidably mounted on said guide for guiding a thread or threads being unravelled from fabric on said holder, a screw shaft for moving said means so as to maintain the same substantially in the plane of the unravelling edge of the fabric as the thread or threads thereof are being unravelled, and a device on the thread guiding means for connecting said means with and disconnecting the same from said screw shaft.
22. In combination, a rotatably mounted fabric supporting drum or the like, a guide arranged adjacent the drum, a carriage slidably mounted on said guide and provided with one or more devices for guiding a thread or threads being unravelled from tubular fabric on said drum, and means for moving said carriage so as to maintain the thread guiding device or devices substantially in the plane of the unravelling edge of the fabric as the thread or threads thereof are being unravelled.
23. In a machine of the character described, a rotatably mounted fabric supporting drum or the like, thread or yarn guiding means movably mounted adjacent the fabric supporting drum, a screw shaft on which the thread or yarn guiding means is mounted, a plurality of mechanisms for unravelling and separately backwinding a plurality of threads or yarns received from a tubular fabric on said drum, and mechanism for turning said screw shaft timed to maintain the thread guiding means substantially in the plane of the unravelling edge of the fabric as the threads or yarns thereof are being unravelled.
24. In a machine of the character described, a rotatably mounted fabric supporting drum or the like, thread or yarn guiding means arranged to take separate

threads or yarns from spaced points on the unravelling edge of a tubular fabric on said drum, a plurality of winding mechanisms for unravelling and separately backwinding the threads or yarns, and mechanism for moving said thread or yarn guiding means so as to maintain the same substantially in the plane of the unravelling edge of the fabric as the threads or yarns thereof are being unravelled.

25. In a machine of the character described a plurality of spaced mechanisms for unravelling and separately backwinding a like number of threads or yarns of a tubular fabric, a drum rotatably mounted between said mechanisms for supporting the tubular fabric and adapted to be rotated by the unravelling and backwinding action of the threads or yarns, and a manually operated 20 brake adapted to be engaged with the drum to control its rotation and thereby regulate the tension of said threads or yarns.

26. In a machine of the character described, a fabric support, a thread or yarn 25 guiding device movably mounted adjacent the support so as to be maintained substan-

tially in the plane of the unravelling edge of a fabric on said support, mechanism for unravelling and backwinding the thread or yarn from said fabric, and a movable thread or yarn guiding device arranged adjacent said unravelling and backwinding mechanism.

27. In a machine of the character described, a rotatably mounted fabric supporting drum or the like, thread or yarn guiding means movably mounted adjacent the drum, mechanism for unravelling and backwinding thread or yarn from a tubular fabric on said drum, mechanism for moving the thread or yarn guiding means so as to maintain the same substantially in the plane of the unravelling edge of the fabric, thread or yarn guiding means slidably mounted adjacent the unravelling and backwinding mechanism, and means for reciprocating said last named thread or yarn guiding means.

In testimony whereof we have signed this specification.

WILLIAM P. TOMS.
WILLIAM R. FOWLER.
